CLAIM

The ornamental design for an insect trap, as shown and described.

DESCRIPTION

FIG. 1 shows a front perspective view of a first embodiment of an insect trap showing my new design.

FIG. 2 shows a top plan view of the insect trap of FIG. 1; FIG. 3 shows a bottom plan view of the insect trap of FIG. 1;

FIG. 4 shows a perspective view of the insect trap of FIG. 1 in use on a plant pot after the outer perforated edge has been removed;

FIG. 5 shows a front perspective view of a second embodiment of an insect trap showing my new design;

FIG. 6 shows a top plan view of the insect trap of FIG. 5; FIG. 7 shows a bottom plan view of the insect trap of FIG. 5; and,

FIG. 8 shows a perspective view of the insect trap of FIG. 5 in use on a plant pot.

(Continued)

The broken lines forming a plant and plant pot in FIGS. 4 and 8 are to show environmental structure and do not form part of the claimed design.
